OPERATING DEVICE FOR RAILWAY CAR COUPLERS

Carl M. Goldinger, Tarentum, Pa., assignor to
Union Metal Products Company, Chicago, Ill.,
a corporation of Delaware

Application November 20, 1931
Serial No. 576,285

6 Claims. (Cl. 213—166)

The invention relates to railway cars and more particularly to a device for operating a railway car coupler which comprises an operating rod operable from the side of the car and connected to the lock of a car coupler so as to unlock the coupler upon rotation thereof and to throw the knuckle of the coupler upon further rotation thereof.

One of the objects of the invention is to provide such an operating device, or more particularly, to provide means to rotate the operating rod of such a device which comprises a depending handle adjacent the side of the car which is connected to the operating rod so that a swinging movement of the handle through a comparatively small arc rotates the operating rod through a larger arc whereby the swinging movement of the handle necessary to operate the coupler is very small as compared to the operating rod having a depending handle rigidly attached to it.

It is necessary to rotate the operating rod about one hundred (100) degrees to throw the knuckle of the American Railway Association standard coupler and the outer depending handle is vertically positioned, therefore, when the handle has been swung sufficiently to throw the knuckle it is in a substantially horizontal position, which means that the operator's arm is in a very poor position to pull very hard upon the handle; in fact, he cannot pull as much at the end of the movement of the handle as he can at the start of such movement which is just exactly the opposite to what is required for proper operation of the coupler.

In my improved arrangement at the end of the one hundred (100) degrees rotation of the operating rod the handle is considerably below a horizontal position so that the operator is in better position to exert a force upon the handle. Furthermore, in my device with a constant force being applied by the operator to the handle the power transmitted thereby to the operating rod is gradually and constantly increased so that very little power is exerted during the first movement of my device when all that is done is to take up the slack between the component parts of the operating device and the coupler. During the second movement when more power is required to unlock the coupler the power exerted by my device has been materially increased by the rearrangement of the parts of my device and during the third movement when still more power is required to throw the knuckle of the coupler the power has been further increased by a still

further rearrangement of the several parts. This comparative short movement of the handle also gives a snap to the operating device which is much more effective than a slow moving device.

Another object of the invention is to arrange the handle and its associated parts so that the operator's hand will not be injured when grabbing the handle, which act is frequently done in the dark and perhaps while signaling the engineer so that he is not watching his hand.

Another object of the invention is to provide such a device that after it is assembled the several associated parts are held together by a single member.

Another object of the invention is to provide a device having a handle requiring a comparatively small swinging movement to operate the device to decrease the possibility of the operator's elbow being hit when coupling two cars and also to decrease the possibility of an operator's body being penetrated by the handle when coupling two cars.

In the drawings:

Fig. 1 shows a typical application of my device to a railway car.

Fig. 2 is a plan view of Fig. 1.

Fig. 3 is a side view of Fig. 1.

Fig. 4 is an enlarged view of the connector between the handle and the operating rod.

Fig. 5 is a side view of Fig. 4 and shows the device in normal position.

Fig. 6 shows the device when the slack has been taken up.

Fig. 7 shows the device when the coupler has been unlocked.

Fig. 8 shows the device when the knuckle has been thrown.

In the drawings the usual parts of the car are shown, such as end wall 2; striking casting 3; coupler carrier; coupler 5; coupler rotor 6 and corner connection 7. The coupler 5 shown is of the type having a rotor or lever arm 6 secured to the bottom of the coupler to which the operating rod 10 is attached so that upon rotation of the operating rod the rotor or lever actuates the coupler to unlock it, or upon further movement, to throw the knuckle. These are called bottom operated couplers. Other couplers, not illustrated, have a lock lifter attached to the lock of the coupler so that upon vertical movement of the lifter the coupler is operated. My device is also applicable to such type of coupler.

In the form illustrated the depending handle 11 is pivotally attached to a bracket 12 mounted upon the car and the lever 14 is also pivotally

secured to preferably the same bracket, which lever 14 has a sliding engagement with the handle. The operating rod 10 has its inner end 16 operatively connected to the coupler and has its 5 outer end slidably and non-rotatably connected to said lever, preferably by having a rectangular portion 18 extending through a rectangular aperture in the lever 14. In this arrangement the lateral movement of the coupler which is transmitted to the operating rod causes the operating 10 rod to slide through the lever so that the lever is not moved sidewise of the car. The handle is preferably bent outwardly at 20 to form a cam surface which arrangement also permits the operating rod to be eccentrically supported by the lever, as shown in Fig. 5, so that the weight of the outer portion of the operating rod causes the lever and the handle to swing toward the car by gravity thus stabilizing the device and preventing it 15 from swinging, which swinging might unlock the coupler or unlock the coupler anti-creep feature. Bending the handle outwardly allows the pivot point of the handle to be placed nearer the car, gives a quicker take-up for the first part of the 20 handle movement and works easier all around than a straight handle.

The operation of the device is as follows; (the degrees given being merely for comparative purposes). First, the handle is moved through an 30 arc A (14°), as shown in Fig. 6, which moves the horizontal axis of the operating rod through arc B (30°) which movement takes up the slack between the component parts of the coupler and the operating device. Second, the handle is moved to arc C (22°), as shown in Fig. 7, which 35 moves the horizontal axis of the operating rod through arc D (40°), whereupon the coupler has been unlocked. Third, the handle is moved through arc E (22°), as shown in Fig. 8, which 40 moves the horizontal axis of the operating rod through arc F (30°), whereupon the knuckle of the coupler has been thrown.

In the preferred form the bracket 12, which is mounted upon the car, is provided with an upper journal 30 and a lower journal 31 and a hood 33—34 above each of said journals. The handle 11 is provided with a hook 36 at its upper end which rotatably engages the upper journal 30 and the lever 14 is provided with a hook 38 at 50 its upper end which rotatably engages the lower journal 31. The lever is provided with spaced apart portions 40—41 (Fig. 1) at its lower end which straddle the handle 11 adjacent the lower part of the cam and the roller 44 is pivotally mounted between said portions of the lever so 55 as to have a rolling engagement with the cam 20 or at least with the outer part of the handle, and any convenient means, such as a cotter 45, may be used to retain the roller between the portions.

The handle engages the lever at points 46 and 47, as shown in Fig. 5, to restrict the swinging movement of the handle toward the car but this desirable object may also be accomplished by the 60 modification shown in Fig. 3, wherein the handle is provided with a pocket 48 which engages the roller 44.

The pocket 48 may be provided by offsetting the handle 11 outwardly so that the offset portion 70 below the connection between the lever 14 and the handle 11, when the device is in normal position, is slightly beyond the roller 44 and its cotter pin 45 so that the operator's hand will not be injured when he grabs the handle. The hood 75

50 is provided to further protect the operator's hand.

The device is assembled as follows: The bracket is applied to the car and the handle is hooked into the upper journal of the bracket and is 80 swung outwardly to a substantially horizontal position. The inner end of the operating rod is then connected to the coupler and its outer end is passed through the aperture in the lever; then the lever is hooked to the lower journal of the bracket; then the handle is lowered to a position between the spaced apart portions of the lever, after which the roller is secured in position. By 85 this arrangement, a single unit (the cotter pin) holds the component parts in operative position. 90

The accompanying drawings illustrate the preferred form of the invention, though it is to be understood that the invention is not limited to the exact details of construction shown and described, as it is obvious that various modifications thereof, within the scope of the claims, will 95 occur to persons skilled in the art.

I claim:

1. In a railway car, an operating means for use with a car coupler operable by the rotation of an operating rod, said means comprising a handle pivotally mounted upon the car, a lever pivotally mounted upon the car having a sliding engagement with said handle, said lever and handle arranged to swing only in a plane substantially 100 normal to the end wall of the car, and an operating rod having its inner end operatively connected to said coupler and having its outer end slidably and non-rotatably connected to said lever. 105

2. In a railway car, an operating means for use with a car coupler operable by the rotation of an operating rod, said means comprising a handle pivotally mounted upon the car provided with an outwardly curved cam portion, a lever pivotally mounted upon the car having a sliding engagement with the cam portion of said handle, said lever and handle arranged to swing only in a plane substantially normal to the end wall of the car, and an operating rod having its inner 115 end operatively connected to said coupler and having its outer end slidably and non-rotatably connected to said lever. 120

3. In a railway car, an operating means for use with a car coupler operable by the rotation of an operating rod, said means comprising a handle pivotally mounted upon the car, a lever pivotally mounted upon the car provided with a portion having a sliding engagement with said handle, and an operating rod having its inner 125 end operatively connected to said coupler and having its outer end slidably and non-rotatably connected to said lever, said handle and said lever cooperatively engaging each other so as to restrict the swinging movement of the handle 130 toward the car. 135

4. In a railway car, an operating means for use with a car coupler operable by the rotation of an operating rod, said means comprising a bracket mounted upon the car provided with an upper journal, a lower journal and a hood above each of said journals, a handle having a hook at its upper end pivotally engaging said upper journal, a lever having a hook at its upper end pivotally engaging said lower journal and having spaced apart portions at its lower end straddling the handle, a roller pivotally mounted between said portions so as to have a rolling engagement with the outer part of said handle, means to retain said roller between said portions, and an operat- 140 145 150

ing rod having its inner end operatively connected to said coupler and having its outer end slidably and non-rotatably connected to said lever, said journals, hoods, hooks and connection 5 between the lever and handle so proportioned and arranged that neither the handle nor the lever can be disconnected from their journals until the handle has been disconnected from the lever.

5. In a railway car, an operating means for 10 use with a car coupler operable by the rotation of an operating rod, said means comprising a bracket mounted upon the car provided with an upper journal, a lower journal and a hood above each of said journals, a handle pivotally engaging 15 said upper journal, a lever having its upper end pivotally engaging said lower journal and having its lower end slidably engaging said handle, and an operating rod having its inner end operatively connected to said coupler and having its outer

end slidably and non-rotatably engaging said lever between its pivotal connection to the bracket and its engagement with the handle.

6. In a railway car, an operating means for use with a car coupler operable by the rotation of an operating rod, said means comprising a bracket mounted upon the car provided with an upper journal, a lower journal, a handle pivotally engaging said upper journal, a lever having its upper end pivotally engaging said lower journal and having its lower end slidably engaging said handle, and an operating rod having its inner end operatively connected to said coupler and having its outer end slidably and non-rotatably engaging said lever between its pivotal connection to the bracket and its engagement with the handle. 80 85 90
